UNITED STATES PATENT OFFICE.

CLARK DOLSON WRIGHT, OF PALESTINE, ILLINOIS.

VEHICLE-TONGUE.

No. 901,054.

Specification of Letters Patent.

Patented Oct. 13, 1908.

Application filed December 9, 1907. Serial No. 405,830.

To all whom it may concern:

Be it known that I, CLARK D. WRIGHT, citizen of the United States, residing at Palestine, in the county of Crawford and State 5 of Illinois, have invented certain new and useful Improvements in Vehicle-Tongues, of which the following is a specification.

The present invention relates in general to vehicles, and more particularly to a sectional 10 tongue having a novel formation which permits grain to be unloaded at the elevator without the necessity of unhitching or unsnapping the breast chains or check lines.

The object of the invention is to design a 15 tongue of this character which is strong and durable in its construction and which enables the driver to retain complete control over his team.

For a full description of the invention and 20 the merits thereof and also to acquire a knowledge of the details of construction and the means for effecting the result, reference is to be had to the following description and accompanying drawings, in which:

25 Figure 1 is a side elevation of a portion of a tongue embodying the invention, the tongue sections being shown as locked in alinement with each other. Fig 2 is a similar view on an enlarged scale showing the locking member as swung upwardly in dotted lines. Fig. 3 is a side elevation showing the tongue sections swung at an angle to each other. Fig. 4 is a top plan view of a portion of the tongue. Fig. 5 is an enlarged 30 detail view of the hinge plates, portions being broken away.

Corresponding and like parts are referred to in the following description and indicated in all the views of the drawings by the same 40 reference characters.

The invention contemplates a vehicle tongue formed in hinged sections which are normally held in alinement with each other by means of a novel locking mechanism.

45 Referring to the drawings, the numerals 1 and 2 designate the sections of the tongue which are normally retained in alinement with each other. Applied to the lower faces of the tongue sections 1 and 2 are the hinge 50 plates 3, the adjacent edges of the hinge plates being formed with coöperating sockets 4 receiving the pivot screw 5. Plates 6 are applied to the upper faces of the tongue sections and are connected to the hinge plates 55 by means of the bolts 7 passing vertically through the tongue. In the present instance

it will be observed that three of these bolts are utilized in connection with each of the plates 6, one bolt being located at the outer end of each of the plates while a pair of 60 bolts in transverse alinement with each other are disposed toward the inner end of each plate. The abutting edges of the plates 6 have the longitudinal slots 8 formed therein and these slots are normally in alinement 65 with each other. It will also be observed that the portions of the tongue sections immediately under the slots 8 are recessed to receive a swinging locking bar 9. The lower corners of the locking bar are rounded or 70 beveled and one end of the bar is pivotally mounted upon a bolt 10 passing transversely through the recess in the tongue section 1, while the opposite end of the locking bar is notched as indicated at 11 and is designed 75 to engage a pin or bolt 12 passing transversely through the recess in the tongue section 2. Attention is directed to the fact that in the present instance each of the bolts 10 and 12 pass through the tongue immediately 80 in rear of a pair of vertical bolts 7 and are therefore prevented from pulling through the tongue sections should an excessive pull be exerted upon the tongue. The swinging end of the locking bar carries an eye 13 for 85 engagement with a cord or like member which extends to the dash-board.

In the operation of the device a slight pull upon the cord serves to raise the locking bar 9 to an upright position whereupon the 90 wagon tongue drops down as far as the breast chains will permit, usually within about twenty inches of the floor. When the wagon is dumped the stub tongue rises up with the wagon, clearing the check lines and leaving the tongue between the horses to keep them apart. After the wagon has been unloaded the horses are started forward and the breast chains caused to tighten and draw the tongue sections into alinement with 95 each other. The locking bar then falls into position and catches upon the pin or bolt 12 so as to retain the tongue sections rigidly in alinement with each other.

Having thus described the invention, what 100 is claimed as new is:

1. The combination of a tongue formed in hinged sections, the said sections being provided with corresponding recesses and one of the recesses having a pin passing transversely across the same, and a locking bar 110 pivotally mounted within the opposite re-

cess and adapted to have an interlocking connection with the pin extending across the first mentioned recess.

2. The combination of a tongue formed in 5 hinged sections, a pin passing transversely through each of the sections, a locking member pivotally mounted upon one of the pins and adapted to engage the opposite pin to hold the two sections in alinement with each 10 other, and a second pin passing transversely through each of the tongue sections immediately in front of the first mentioned pin and arranged transversely with respect thereto so as to reinforce the same and prevent it from pulling out through the end of 15 the tongue section.

3. The combination of a tongue formed in

sections, pivotally connected hinge plates secured to one side of the sections, plates secured to the opposite side of the tongue sections and provided with slots, the said slots being in alinement with each other and the portions of the tongue sections under the slots being recessed, and a swinging locking member pivotally mounted within the recess 20 of one of the tongue sections and adapted to be received within the recess of the opposite tongue section and have an interlocking connection with the said opposite tongue section. 25

CLARK DOLSON WRIGHT.
